UNITED STATES PATENT OFFICE.

SAMUEL HELLER, OF NEW YORK, N. Y.

DESIGN FOR PRECIOUS OR SEMIPRECIOUS OR SYNTHETIC STONE OR AN IMITATION THEREOF.

47,722.

Specification for Design. Patented Aug. 17, 1915.

Application filed November 12, 1914. Serial No. 871,795. Term of patent 7 years.

To all whom it may concern:

Be it known that I, SAMUEL HELLER, a citizen of the United States, residing at the borough of Manhattan, in the city, county, and State of New York, have invented a new, original, and ornamental Design for a Precious or Semiprecious or Synthetic Stone or an Imitation Thereof, of which the following is a specification, reference being had therein to the accompanying drawings, which form a part thereof.

In the drawings: Figure 1 is a plan view of a cut stone embodying my design; Fig. 2 is a side view thereof; and Fig. 3 is an end view thereof.

I claim:

The ornamental design for a precious, or semi-precious, or synthetic stone, or an imitation thereof consisting of a flat table centrally of the crown having two triangular facets at each end thereof, and having at each side thereof and extending at an angle toward the girdle, a large central table with two triangular facets at each end thereof, and of a pavilion having facets thereon.

SAMUEL HELLER.
